Application December 30, 1938, Serial No. 248,462

18 Claims. (Cl. 28—57)

This invention relates to the art of treating artificial fibers and particularly to an improved apparatus for treating the fibers continuously on a commercial scale.

Although the invention is broadly applicable to the processing of many kinds of synthetic fibers, such as those made from the cellulose derivatives, vinyl resins and the like, it is primarily designed for the treatment of filaments made from the vinyl resins. Of these, the invention is particularly directed to the processing of filaments made from the vinyl ester resins which may result from the conjoint polymerization of vinyl halides with vinyl esters of aliphatic acids. Those resins are preferred which are made by the conjoint polymerization of vinyl chloride with vinyl acetate, containing between about 70% and about 95% vinyl chloride in the polymer and having high average macromolecular weights, preferably in excess of 15,000. Molecular weights referred to herein are those calculated by means of Staudinger's formula from viscosity determinations of solutions of the resins.

In the production of artificial yarns, after the plastic has been spun into filaments, it is usually necessary to pass the yarn through one or more processing steps in order to produce a yarn of suitable physical properties. The most common treatment consists in stretching the yarn to increase its strength. For certain types of artificial fibers additional treatments are necessary, in order to render permanent the advantages gained in the stretching process. Thus, with highly elastic fibers, such as those produced from the vinyl resins described above, the stretch imparted to the yarn must be "set" or else the yarn will contract upon being unwound from the bobbin. The setting treatment may comprise aging the yarn for a period of time under tension or subjecting it to elevated temperatures below its softening point, either dry or submerged in a liquid medium. In the case of some artificial yarns, notably those produced from vinyl resins, the stretching operation imparts a hard "feel" or "hand," which must be removed in order to produce a commercially desirable textile. This hardness of texture may be removed by "flexing" the yarn or passing it over rollers or guides of small diameter at fairly high speeds.

The preparation of filaments from the resins resulting from the conjoint polymerization of vinyl halides with vinyl esters of aliphatic acids is described in United States Patent No. 2,161,766,

issued June 6, 1939, to E. W. Rugeley, T. A. Feild, Jr., and J. F. Conlon.

An object of this invention is to provide a machine for continuously effecting an orientation of the macromolecules or micellae of the molecular structure of synthetic fibers or yarns by elongation, either while passing them through a heated chamber or without subjecting them to heat other than normal atmospheric temperatures, and by processing them either wet or dry, to increase their strength.

Another object of this invention is to provide a machine designed to elongate synthetic yarns continuously at various percentages of stretch on a commercial basis.

Other objects of the invention include the provision of a machine for reducing the denier of synthetic filaments to a size smaller than can be produced in the spinning or extruding operation; the provision of a machine for the continuous setting or stabilizing and flexing of synthetic yarns simultaneously by passing them through one or more heating and cooling cycles; the provision of a machine for the continuous flexing of synthetic fibers or yarns by running them over rollers of small diameter to effect a bending action; either in the presence of water or while in the dry state; and the provision of a means for producing delustered finished yarn uniformly by elongation.

Special objects of the invention include the provision of yarn processing mechanisms of unitary construction, any number of which may be duplicated, and each of which may be capable of individual and selective operation; the provision of a machine including a plurality of such unitary yarn processing mechanisms in which a separate clutch and brake device is provided for each unit, and adapted automatically to disengage it from the source of power and quickly stop it independently of the other units upon breakage of the yarn or upon passage of the end of the yarn through the processing mechanism, said device also including means for starting said unit and for bringing it up to speed evenly while it is being coupled to the common source of power without, however, interfering with the other units of the machine.

Other special objects include the provision of stretcher rolls having surfaces of a phenol-formaldehyde resin bonded with a base of paper, canvas or linen, and feed or take-up friction rollers used to drive the bobbins having surfaces of rubber; and the provision of a yarn guide which traverses the take-up bobbin as the yarn

is wound thereupon and aids in building a uniform yarn cake by maintaining a small but substantially constant distance between the point of contact of the guide with the yarn and the point of tangency of the yarn on the bobbin.

These and other objects of the invention will be evident from the following description, having reference to the annexed drawings:

In the drawings, Fig. I, is an elevational view of a yarn processing machine embodying the principles of the invention;

Fig. II is a schematic diagram of a yarn processing unit, Y_2 of Fig. I, adapted to stretch the yarn while in contact with a liquid;

Fig. III is a schematic diagram of a yarn flexing and setting unit employing a common drive for the feed and take-up bobbins as shown in the yarn processing unit Y_3 of Fig. I;

Fig. IV is a schematic diagram of that portion of the yarn processing unit Y_3 of Fig. I wherein the setting and flexing of the yarn takes place;

Fig. V is an end elevational view of the yarn processing machine shown in Fig. I;

Fig. VI is a sectional view of the yarn processing machine shown in Fig. I, taken approximately along the line VI—VI of Fig. I, and showing on the rear side of the machine a yarn processing unit corresponding to Y_2 of Fig. I;

Fig. VII is a sectional view taken approximately along the line VII—VII of Fig. I, and showing a plan view of a unit corresponding to Y_2 of Fig. I on the rear side of the machine; and

Fig. VIII is a sectional view taken approximately along the line VIII—VIII of Fig. I, and showing a duplicate unit on the rear side of the machine.

Referring to Fig. I, the principles of the invention are shown as applied to a machine adapted to drive a plurality of yarn processing units, each of which may perform the same or a different operation on the yarn being treated. The machine disclosed comprises a frame F upon which is mounted a power transmission mechanism P adapted to drive a common drive shaft D from which a plurality of yarn processing units, such as Y_1 , Y_2 and Y_3 , are independently driven. The power transmission mechanism P is likewise adapted to drive a reciprocating bobbin traversing mechanism T, as well as a common reciprocating device R adapted to actuate a trip-off mechanism Tr for each individual processing unit Y.

The yarn processing unit Y_2 , in Fig. I, is adapted to stretch the yarn while the same is in contact with a liquid. This unit is schematically represented in Fig. II of the drawings. Referring to Figs. I and II, a bobbin 10, loaded with the yarn to be processed, is placed in a bobbin holder 12 in position relative to a friction feed roll 14 so that the latter frictionally engages the yarn and meters it off at a given uniform rate, there being sufficient friction between the yarn on the bobbin 10 and the friction feed roll 14 to maintain the tension of the yarn caused by the stretching process. The feed roll 14 is made of, or covered with, a suitable material such as rubber which has a high coefficient of friction to insure good traction and sufficient resilience to prevent injury to the yarn. The feed roll 14 rotates in a bath 16 that supplies a film of water or other liquid to the yarn. The yarn thus wetted is less susceptible to injury while passing through the process.

The yarn is fed from the bobbin 10 to, and 75

approximately one-half turn around, a friction roll 18 partly submerged in a bath 19, thence upwardly and a half turn around a canted idler roll 20 (i. e. the idler roll 20 is positioned at a slight angle to the roll 18 so that the yarn travels from one end of the rollers to the other in a helical path) and downwardly around the roll 18 again, preferably making a minimum of four turns around both rolls 18 and 20. The purpose of the canted roll 20 is to separate or space the progressive wraps of yarn to prevent abrasion of one wrap against another as the yarn is stretched away from the friction roll 18 at the point of tangency. It is at this point that the stretch takes place and is the most vulnerable spot in the stretching process. The roll 20 is mounted so that its axis lies in the same plane as the axis of the friction roll 18, but canted so that the end of the roll 20 which carries the last wrap of yarn before the latter leaves the friction roll 18 on the next half turn is nearer the friction roll 18. The numerous turns, or wraps of yarn around the rolls 18 and 20 are for the purpose of preventing slippage of the yarn, due to increased tension as it leaves the roll 18. The number of turns or wraps that are required is determined by the denier of the yarn being processed, and by the temperature of the liquid bath 19 in which the friction roll 18 is partly submerged. In practice, it is often desirable to drive the roll 20 by positive means in order to relieve the yarn of any unnecessary stress or possible abrasion. This is most easily accomplished by placing a rubber band around both the rolls 18 and 20 so that the friction roll 18 will drive the roll 20 upon rotation. For this purpose, a groove 21 is provided on the end of the roll 20, over which the elastic band is passed and which is sufficient to retain the band in position during operation. This positive drive is especially necessary when very fine denier yarn is being processed.

The bath 19, being water or other liquid, is varied in temperature to suit best operating conditions. For stretch percentages up to 200% the temperature will range between about 5° and about 95° C., and for percentages from 100% to 300% the temperature will range from 30° to 150° C. Obviously, if temperatures above 100° C. are employed, a liquid boiling at a higher temperature than water, such as the glycols or glycerine, would be employed.

In order to insure the positive feeding of the yarn at a substantially constant velocity to the roll 18, an idler sheave 22 is provided. It is positioned at a distance from the supply bobbin 10 equal to at least about three times the wrapped length of the bobbin. This distance is indicated in Fig. II as $3x$, with the wrapped length of the bobbin 10 indicated as x . The purpose of so positioning the idler sheave 22 is to minimize the effects of a varying length of yarn between the bobbin 10 and the roll 18, due to the angularity of the yarn when unwinding from the ends of the bobbin.

The friction roll 18 is constantly rotated in the bath 19. To withstand this condition as well as possess characteristics of good traction and yet be readily machinable to a smooth surface which will not be susceptible to scoring or blemishing when in service, a phenol-formaldehyde resin bonded with a base of paper, canvas or linen is used. An outstanding advantage of using this material for this purpose is long life without

distortion or change in size, which insures constant peripheral speeds indefinitely.

The yarn is caused to be stretched by rewinding it on a take-up bobbin at a greater speed than the speed at which it is unwound from the supply bobbin 10. Between a take-up bobbin 24, which is positioned against a friction roll 26 by a holder 28 so that the roll 26 frictionally drives the bobbin 24 (in the same manner as the bobbin 10 is driven by the roll 14), and the roll 18, the yarn passes over an idler sheave 30 that is mounted upon the traverse mechanism T, which latter is reciprocated to cause the yarn to be wound uniformly on the take-up bobbin 24. For the same reason that the idler sheave 22 is positioned at a distance from the supply bobbin 10 equal to at least three times the wrapped length of the bobbin, the idler sheave 30 is similarly positioned with respect to the friction roll 18. The frictional surface of the roll 26 is rubber, as is the case with the roll 14, so that when the roll 26 is driven at a greater peripheral speed than that of the roll 18, it correspondingly rotates the bobbin 24 faster than the yarn is unwound from the roll 18, thereby effecting a stretching of the yarn between the bobbin 24 and the roll 18.

The flexing and setting operations of this invention may be performed by several methods. The preferred method comprises passing the yarn through a similar unit as used for the stretching operation, threading the yarn, for example, from the supply bobbin 10 around the various rolls and sheaves and rewinding it on the take-up bobbin 24 as illustrated in Fig. II and described above for the stretching operation. The essential difference between these operations of stretching and of flexing and setting resides in the temperature of the water bath 19 (usually above room temperature) and the speed ratio between the supply bobbin 10 and the take-up bobbin 24. For flexing and setting, the peripheral speeds of both bobbins are the same, or the speeds are at a 1:1 ratio. Thus the yarn is passed continuously through a heating and cooling cycle (when withdrawn from the bath into the air) and is prevented from contracting by the positive unwinding and rewinding of the bobbins as it is stabilized or set in the water bath 19, and flexed by bending over the canted roll 20. The temperature that is used for stabilizing or setting depends on a number of factors including the speed of operation, the number of wraps around the friction roll 18 that submerges the yarn in the water, the percentage of elongation the yarn has been given, and the desired texture of the finished yarn, as described in the above-mentioned Patent No. 2,161,766.

The yarn processing unit Y₃, of Fig. I, is adapted to flex and set the yarn while it is in contact with a liquid, and differs from the yarn processing unit Y₂ in that, (1) only one roll is employed to drive both the feed and take-up bobbins, and (2) the yarn is flexed by passing it around a plurality of rollers having very small diameters, rather than a single, larger roll, such as the idler roll 20 of the yarn processing unit Y₂. If desired, the yarn may be flexed by passing it around a single flexing roll, such as the idler roll 20 of Fig. II (also shown schematically as idler roll 43 in Fig. III), rather than a plurality of very small diameter rollers, and this is preferred where the supply and take-up bobbins are driven by separate friction rolls, such as is shown in the yarn processing unit Y₂. Both types of flexing rollers are interchangeable and may be

used on any yarn processing unit, the type being selected, of course, according to the method of driving the supply and take-up bobbins. The method of flexing and setting the yarn, wherein the bobbins are driven by a common roll, is schematically shown in Fig. III, and the use of a plurality of small rollers for flexing the yarn is shown schematically on a relatively enlarged scale in Fig. IV.

- 5 10 Referring to Figs. I and III, a supply bobbin 32 is placed in a bobbin holder 34 that positions the yarn cake of the bobbin 32 against feed roll 36. The friction feed roll 36 rotates the bobbin 32, thus metering off yarn at a given uniform rate 15 in the same manner as described in connection with the action of roll 14 of Fig. II. From the supply bobbin 32 the yarn is passed over an idler sheave 38, thence around a friction roll 40 one-half turn and, as shown in Fig. III, over a canted 20 idler roll 43, preferably making about four wraps in the same manner as described for the stretching operation. In the unit Y₃ of Fig. I, the yarn passes from the roll 40 over, under and over the flexing rollers 42, preferably making about four 25 wraps as shown schematically in Fig. IV. The friction roll 40 is immersed in a bath 41 in the same manner as described for the stretching unit. If desired, the rollers 42 may also be submerged in the bath 41, as shown in the unit Y₃ of Fig. I. From the friction roll 40 the yarn 30 passes upwardly to an idler sheave 44 mounted on the traverse mechanism T in the identical manner as for the idler sheave 30, shown schematically in Fig. II. From the idler sheave 35 44 the yarn passes to a take-up bobbin 46 placed in a bobbin holder 48 which positions the bobbin 46 on the friction roll 36 opposite the bobbin 32. Since the bobbin 32 and the bobbin 46 are both driven from the common friction roll 36, a 1:1 40 ratio of unwinding the yarn from the bobbin 32 and winding it on the bobbin 46 is insured.

The flexing rollers 42, shown schematically in Fig. IV, may be varied in diameter from 0.030 to 1.5 inches, but it has been found that steel rollers 0.125 inch in diameter are very effective for flexing the yarn, yet large enough to avoid difficulties of mechanical construction. The extreme speeds at which the rollers 42 must rotate (normally 8,000 to 20,000 R. P. M.) necessitates 45 the use of bearing materials having a low coefficient of friction, and preferably capable of being sufficiently lubricated by water, or whatever fluid is used for the setting bath in which they may be immersed. In addition the bearing surfaces should possess long wearing qualities and non-corroding properties. Bearings possessing the above characteristics may be of the point type as shown in Fig. IV or they may be plain shoulder bearings, made of carbon.

60 Another method of setting or stabilizing the yarn is by bringing water at the required temperature in contact with the stretched yarn as it is being rewound on the take-up bobbin. This may be done as shown in Fig. II, by rotating the friction roll 26 in a water bath 50, thus carrying a film of water to the yarn on the bobbin 24, or by directing a jet of water from a nozzle 52 upon the yarn as it is being wound upon the bobbin 24. Yarn which is set by these 65 methods is usually flexed by a subsequent operation in the event that a very soft textured yarn is required.

In the stretching operation, or in the flexing operation wherein a yarn processing unit of the type indicated in Fig. I, as Y₂, is employed, the

yarn from the supply bobbin may be unwound by other than the positive methods disclosed above. An alternate method consists in mounting the bobbin on a spindle supported on either end by bearings, where it rotates as the yarn is metered off by being pulled around the friction roller, indicated as roll 18 in Fig. II. The bearings for the spindle may be either point bearings or plain shoulder bearings. Ball, roller or other anti-friction bearing may also be adapted to this use.

Referring to Fig. I a center drive channel 54 and end frames 56 and 58 form the main structure of the machine and support directly or indirectly all parts of the machine. The end frames 56 and 58 are connected by the center drive channel 54 and an upper frame support 60. A spacer (not shown) may be placed between the end frames 56 and 58 and below the center drive channel 54 to separate the lower parts of the end frames 56 and 58 and to increase the rigidity of the machine. The center drive channel 54 is a rugged cast section designed to carry all the intervening weight between the end frames 56 and 58. In the center of its hollow section is mounted the main drive shaft D which rotates in ball bearings 62. A main transmission gear box 64 is supported by the end frame 56 and aligns a worm shaft 66 with the main drive shaft D. Shafts 66 and D are connected together by a flexible coupling 68. The upper frame support 60, in addition to connecting the end frames together, carries bobbin holder parts and anchors the individual yarn processing units, thereby increasing the rigidity of the entire system.

The power transmission mechanism P is designed to transmit power for all movements of the machine, to synchronize all functions of the various parts and to provide a means of changing the speed at which the traverse mechanism T reciprocates in proportion to the peripheral speed of the take-up bobbins. Referring to Figs. I and V, the drive shaft 66, which is an integral part of a worm drive 70, is adapted to be rotated by a chain drive sprocket 72 (shown in Fig. I) which is connected by a chain 74 to a motor 76, the slack in the chain being taken up by an idler sprocket 78. A worm gear 80 which is driven by the worm drive 70 is mounted on a shaft 82 that drives a shaft 84 through spur change gears 86 and 88. On the shaft 82 is also mounted a spur gear 90 which drives an eccentric 92 through a spur gear 94. The eccentric 92 actuates a connecting rod 96 which in turn operates the reciprocating mechanism R. The eccentric 92 rotates on the shaft 84 at a constant speed, while the shaft 84 rotates at different speeds depending on the ratio of the number of teeth in the gears 86 and 88. Fixed on the shaft 84 is a spur gear 98 that drives a spur gear 100 on a drive shaft 102. On the shaft 102 are mounted two uniform-rise cams 104 that actuate the traverse mechanism T. The worm 70, shafts 82, 84 and 102 rotate in bearings mounted in the gear box 64. The gears and mechanism are accessible through an opening at the top of the gear box 64 by removing a cover 108 and through the side by removing a cover 106.

The traverse mechanism T is designed to guide the processed yarn transversely across the take-up bobbins between their flanges while the yarn is being wound, in such a manner as to build a straight, uniform cake. Referring to Figs. I and V, traverse bars 110 reciprocate in bearings 112 where they are keyed to prevent rotation. On the traverse bars 110 are mounted thread guide

holders 114 which are held in the proper position by vernier adjustments 116 (shown in Figs. I and VI). Assembled on the thread guide holders 114 are wire type guides 118, shown in detail in Fig. VI, and the thread guide idler sheaves 30, 44, and the like for each yarn processing unit, over which the yarn rides as it changes from a vertical path to one in the direction of the bobbin.

The traverse bars 110 are adapted to be reciprocated by the combined action of the cams 104 and tension springs 120 which move traverse bar actuating levers 122, which latter are connected to the traverse bars 110 by drag links 124 and drag link clevis 126. On the traverse bar actuating levers 122 are mounted eccentric octagonal cam followers 128 normally adapted to slidably engage the cams 104 and which index once every revolution of the cams by virtue of the undercut portions 130, causing the traverse bars 110 to shift reversing points progressively four times in each direction. The cam followers 128 may have a different number of sides from eight, although this number permits the build-up of a very uniform yarn cake on the take-up bobbins. The purpose of this movement is to compensate for the dwell of the yarn being wound on the bobbin at the end of the stroke, during which time the yarn would build an uneven cake if no correction were provided.

The wire, or slotted, guide 118 is designed with a profile curved so that the distance from the point of contact of the yarn against the guide to the point of tangency of the yarn on the bobbin, or yarn cake (marked "d" in Fig. VI), is constant as the yarn is wound. By setting the guide 118 close to the bobbin, the distance which the traverse bar 110 must travel, upon reversal of direction, to change the location of the thread being wound on the bobbin is minimized, with the consequent reduction in the dwell of the yarn at the end of each stroke and the production of a more uniform yarn cake on the bobbin. By employing a guide having the profile described, the distance *d* may be maintained constantly at a minimum, thus permitting adjustment of the eccentricity and size of the cam follower 128 to shift the reversing point of the traverse bar 110 the right amount to compensate completely for the small, but unavoidable, amount of dwell of the yarn at the end of each stroke.

The reciprocating mechanism R is designed to actuate the individual, identical trip-off mechanisms T_{r2} , T_{r3} , etc. on the units Y_2 , Y_3 , etc. respectively. The connecting rod 96 reciprocates the rods 132 located on each side of the center drive channel 54, through a cross bar 134, the opposite ends of which are fixed to the rods 132. The rods 132 are adapted to reciprocate in guide brackets 136, shown in Figs. I and VI, that are mounted on but extend outwardly from the center drive channel 54. On the rods 132 are mounted trip-off arms 138, shown in Figs. I, VI and VIII, one for each trip-off mechanism T_r on each yarn processing unit, in order to furnish the power to the trip-off mechanisms T_r to disengage the units from the central drive shaft D and stop them. Further details of the trip-off mechanisms T_r are described below.

The yarn processing operations are performed by the individual units Y_1 , Y_2 , Y_3 , etc. with the aid of the previously mentioned auxiliary parts. The individual yarn processing unit, of which there can be many assembled on a machine, is

primarily a positive type rewinding device that can be operated independently of any other unit at equal or differential peripheral speeds between the unwinding or feed bobbins and the rewinding or take-up bobbins to obtain any required percentage of stretch or to rewind without stretch during the flexing and setting operations.

Referring to Fig. VII, which shows a cross sectional view of the yarn processing unit Y_2 taken along the line VII-VII of Fig. I, and a plan view of a similar unit which may be located on the other side of the central drive channel 54 , the power for the operation of the units is transmitted from the center drive shaft D through the bevel gears 140 and 142 . The bevel gear 142 is mounted on a clutch driving sleeve 144 which rotates in ball bearings 146 . Through the center of the clutch sleeve 144 is a transmission drive shaft 148 which carries the friction clutch parts 150 to 166 inclusive. The clutch parts consist of a driving plate 150 fixed to one end of a shift sleeve 152 which is splined to the shaft 148 ; a brake plate 154 fixed to the opposite end of the shift sleeve 152 ; a compression plate 156 having an extended hub portion 158 slidably mounted upon the shift sleeve 152 (preferably splined thereto) between the plates 150 and 154 ; compression springs 160 between the plates 150 and 156 ; a clutch lining disc 162 fixed to the flanged portion of the clutch driving sleeve 144 ; and a clutch shift ring 164 connected to the hub 158 through a ball bearing 166 . The function of this clutch is to connect the clutch driving sleeve 144 to the transmission drive shaft 148 in such a manner that there will be little or no slippage when the yarn processing unit has been brought up to speed, but that the unit will be gradually accelerated when beginning operation, particularly to facilitate starting of the stretching operation.

When the clutch is disengaged, the stop plate 154 is pushed against a brake lining disc 168 which brings the disengaged unit to rest almost instantly.

On the shaft 148 is keyed a spur gear 170 that drives a gear 172 . The gear 172 is fixed to one end of friction feed roll shaft 174 that extends through a boss on the front cover and over the water bath 16 . On the other end of the shaft 174 and extending down into the bath 16 is friction feed roll 14 . The drive shaft 148 also extends through the front cover of the water bath 19 and has mounted on it a stretcher roll adapter 176 which holds the stretcher roll 18 .

Referring to Fig. I and Fig. VII, the take-up bobbin 24 and its associated parts are likewise driven through the clutch and brake mechanism previously described. This is accomplished by providing a bevel gear 178 on a horizontal shaft 180 , which latter is driven by a spur gear 182 . The spur gear 182 is driven by a spur gear 184 which is keyed to the shaft 148 . When changing from one percentage of stretch to another, the spur gears 182 and 184 are replaced with others having the required tooth ratio. The clutch mechanism parts 150 to 166 inclusive, the spur gears 170 , 172 , 182 and 184 , the shaft 180 and the bevel gear 178 are enclosed in a gear box 186 .

Referring to Fig. I, and to Fig. VI (which shows a yarn winding mechanism, a trip-off mechanism and means for driving the yarn winding mechanism identical in all of the yarn processing units), a torque tube 188 extends upward

from the gear box 186 to a gear box 190 (shown in cutaway in the yarn processing unit Y_1 of Fig. I). The torque tube 188 is constructed of a flanged tube in which a vertical shaft 192 rotates in ball bearings 194 and 196 . On the lower end of the shaft 192 is a bevel gear 198 which engages the bevel gear 178 , while on the upper end is a bevel gear 200 . The purpose of this tube is to take the torque of the gears, support the gear box 190 and to enclose the moving parts to retain the lubricant and exclude foreign matter.

The gear box 190 is mounted on the torque tube 188 and contains a bevel gear 202 and horizontal shaft 204 . The friction take-up roll 26 is mounted on the shaft 204 . The take-up bobbin 24 is supported in the bobbin holder 28 which positions the bobbin on the friction take-up roll 26 in the same manner in which the feed bobbin 10 of yarn processing unit Y_2 is positioned on the friction feed roll 14 by the bobbin holder 12 .

In Fig. VII the bobbin holder 28 hinges on a bracket 206 which permits the bobbin to rise as it is being filled with yarn. The bobbin holder 28 has a hinged side 208 that is kept tight against the end of the bobbin by a tension spring 210 . The hinged end 208 can be opened to a position of approximately 45° , at which position the spring passes behind the center line of a hinge 212 , thus holding the bobbin holder 28 open against a stop. Extending from the gear box 190 is an idler bracket 214 that supports the roller thread guides 22 . These roller thread guides, as previously explained, are positioned at this elevation to reduce the angularity of the yarn as it is unwound from the supply bobbin 10 .

As previously stated, the individual yarn processing units Y_1 , Y_2 , Y_3 , etc. are started and stopped by a special friction clutch and brake. This clutch is controlled manually for starting the unit, and the unit is automatically stopped if the yarn being processed should break or when an end is reached. Referring to Figs. I, VI and VIII, the machine is started by moving a clutch-engaging lever 216 inwardly until a clutch-actuating lever 218 engages with a clutch latch 220 which is held in place by a clutch latch spring 222 . The clutch-actuating lever 218 is also held under tension by a spring 224 which causes it to reverse when the clutch-latch 220 is disengaged. The levers 216 and 218 are fixed on a clutch lever shaft 226 and rotate a clutch shift fork 228 to engage the clutch (Fig. VII).

The unit can be stopped either manually or automatically by means of the trip-off mechanism T_{r2} (Fig. I). As the yarn goes from the stretcher roll 18 of the unit Y_2 (or the roll 40 of the yarn processing unit Y_3) to the thread guide roller 30 mounted on the traverse bar 110 , it passes through a wire guide 230 which is secured in a trip lever 232 (Fig. VIII). The trip lever 232 pivots on a rod 234 that extends between bosses on a trip mechanism holder 236 . The wire guide 230 is prevented from moving outwardly by a stop 238 keeping it always unbalanced inwardly. While the yarn is kept taut by the processing operation, the trip lever 232 and the wire guide 230 are held in a vertical position, but when a break in the yarn occurs or when an end is reached they fall backward on a balance lever 240 . The balance lever 240 is mounted in a carriage 242 which is fixed on pins 244 . This assembly slides transversely in the trip mechanism holder 236 . When the trip

lever 232 falls on the balance lever 240 the latter becomes overbalanced and the low end 246 tips upward in the path of the trip-off arm 138, which moves the lever and the carriage assembly along, causing one of the pins 244 to disengage the latch 220, releasing the friction clutch to stop the unit. The balance lever 240 can also be overbalanced manually to cause the unit to stop.

When yarns having specific characteristics are desired, the condition under which they are processed can be predetermined accurately and later duplicated to produce yarn uniformly within commercial limits.

For example, to obtain a finished yarn of 100 denier having a twist of four turns per inch, either right or left hand, having a texture of extreme softness, possessing flexibility and having a delustered finish, filaments spun from the vinyl resins previously described will be processed in the following manner:

In preparing the yarn for the stretching operation, sufficient filaments are assembled on a doubling and twisting machine to form a yarn of 277 denier and are then twisted together with eleven turns per inch and wound on a suitable bobbin or spool.

A supply of yarn thus prepared is placed on the stretching machine where it passes from a supply bobbin to and around the stretcher rolls to be subjected to a heat treatment by rotating the stretcher roll partially submerged in a water bath maintained at about 92° C. The yarn passes around the stretcher and canted rolls six turns or laps, which has been found to give the yarn the proper time exposure when being processed at a speed of approximately 80 meters per minute. The yarn is then wound or reeled onto the take-up bobbin at a peripheral speed of 277% that of the unwinding speed of the supply bobbin, resulting in a 177% stretch and reducing the yarn from 277 denier to 100 denier.

The flexing and setting operation is performed in the same manner except that the supply bobbin and the take-up bobbin operate at the same peripheral speed. The yarn passes through a heating and cooling cycle as before, making six turns or laps around the roll known as the stretcher roll in the stretching operation and the canted roll, where the proper time exposure is made in a water bath that is maintained at about 82° C. The yarn, after being rewound on the take-up bobbin, is then finished ready for coning or packaging as required.

The spun yarn before stretching has a strength of 0.85 gram per denier and an elongation or extensibility of about 130%. After the yarn has been stretched 177%, set and flexed, its strength may increase to 2.7 grams per denier with an elongation of 14%.

Many modifications of the invention will be apparent to those skilled in the art and it should not be limited other than as defined by the following claims.

I claim:

1. Apparatus for processing artificial textile yarns by stretching, flexing, setting and the like, comprising in combination, at least one individual yarn processing unit including frictionally driven supply and take-up bobbins, a combined clutch-and-brake mechanism, means for driving at least one of said bobbins through said clutch-and-brake mechanism, and means for maintaining a predetermined ratio of speed between said supply bobbin and said take-up bobbin; said clutch-and-brake mechanism being normally

urged toward clutch-disengaging and brake-engaging position; means for holding said clutch-and-brake mechanism in position for driving at least one of said bobbins; trip-off control means held in position by the yarn in process; and a reciprocating member adapted to cooperate with said trip-off control means upon the discontinuity of the yarn in process for releasing said clutch-and-brake holding means.

5 2. The combination as claimed in claim 1, wherein said combined clutch-and-brake mechanism comprises a clutch disc driven by said driving means, a second clutch disc adapted to engage with said first clutch disc, at least one clutch spring, a lever, an axle, a carriage slidably mounted on and adapted to be moved along said axle by said lever, said second clutch disc being connected to said carriage by said clutch spring, a brake disc mounted on said carriage, a second 10 brake disc with which said first brake disc is adapted to engage frictionally; the construction and arrangement being such that movement of said lever in one direction causes said clutch discs to be engaged and said brake discs to be 15 disengaged, and movement of said lever in the reverse direction causes said clutch discs to be disengaged and said brake discs to be engaged.

3. An apparatus for processing artificial textile yarn by stretching, flexing, setting and the like, comprising in combination at least one individual yarn processing unit having: a frictionally driven supply bobbin; a frictionally driven take-up bobbin; a combined clutch-and-brake mechanism composed of a driving clutch disc, a

20 second clutch disc adapted to engage with said driving clutch disc, a lever, an axle, a carriage connected to said lever being slideably mounted on said axle, at least one clutch spring, said second clutch disc being connected to said carriage

25 by said clutch spring, a brake disc mounted on said carriage, a second brake disc adapted to be frictionally engaged with said first brake disc, and an automatic clutch-disengaging and brake-engaging means; a power transmitting means

30 connecting said clutch-and-brake mechanism to at least one of said bobbins, means for maintaining a predetermined ratio of speed between said supply bobbin and said take-up bobbin; means for driving said clutch-and-brake mechanism; a reciprocating member; a trip-off control means

35 comprising an operating means engageable with said reciprocating member to actuate said automatic clutch-disengaging and brake-engaging means; a wire guide normally held in position by the yarn in process, said guide being adapted upon discontinuity of the yarn in process to actuate said operating means and to urge the latter into the path of said reciprocating member, thereby moving said operating means to actuate said automatic clutch-disengaging and brake-engaging mechanism.

4. An apparatus for processing artificial textile yarns wherein such yarns are wound on bobbins, comprising a feed roller adapted to frictionally engage a feed bobbin, a take-up roller frictionally engaging a take-up bobbin, a yarn processing roller, an idler roller positioned at a distance from said processing roller, a common driving means for positively driving said feed roller, said take-up roller and said processing roller, and means for so maintaining said take-up roller at a greater peripheral speed than the peripheral speed of said feed roller that the yarn is stretched while passing around said processing roller and said

idler roller when going from said feed bobbin to said take-up bobbin.

5. An apparatus for processing artificial textile yarns wherein such yarns are wound on bobbins comprising a feed bobbin, a take-up bobbin, a common driving roller to frictionally engage said feed bobbin and said take-up bobbin, a yarn processing roller, at least one idler roller positioned at a distance from said processing roller, and a common driving means for positively driving said common driving roller and said processing roller, such that yarn is flexed while passing around said processing roller and idler rollers when going from said feed bobbin to said take-up bobbin.

6. An apparatus as claimed in claim 4 in which said processing roller and said idler roller are substantially cylindrical in shape, and the axis of said idler roller is disposed at a slight angle with respect to the axis of said processing roller, whereby yarn looped around said rollers will be conveyed from one end of the rollers to the other end.

7. An apparatus as claimed in claim 5 in which said processing roller and said idler roller are substantially cylindrical in shape, and the axes of said idler rollers are disposed at a slight angle with respect to the axis of said processing roller, whereby yarn looped around said rollers will be conveyed from one end of the rollers to the other end.

8. An apparatus as claimed in claim 4 in which said processing roller is at least partially immersed in a liquid, and the surface of said processing roller is made of a phenol-aldehyde resin.

9. An apparatus as claimed in claim 5 in which said processing roller and said idler rollers are immersed in a heated liquid for setting or stabilizing the yarn.

10. An apparatus as claimed in claim 4 having means for applying a heated liquid to the yarn as it is wound on the take-up bobbin for setting the yarn.

11. An apparatus for processing artificial textile yarns wherein such yarns are wound on bobbins, a yarn processing unit comprising a combined clutch-and-brake mechanism whereby the unit may be manually started and brought up to speed and substantially instantaneously stopped upon the discontinuity of the yarn in process; a feed roller adapted to frictionally engage a feed bobbin, the operation of said feed roller being positively controlled by said clutch-and-brake mechanism; a take-up roller frictionally engaging a take-up bobbin, the operation of said take-up roller being positively controlled by said clutch-and-brake mechanism; a yarn processing roller positively controlled by said clutch-and-brake mechanism and adapted to pass the yarn through a liquid medium; an idler roller posi-

tioned at a distance from said processing roller and being disposed at a slight angle with respect to said processing roller whereby a thread looped around said rollers will be conveyed from one end to the other; said take-up roller being positively driven at a peripheral speed greater than that of said processing roller whereby the yarn in process is stretched a definite and predetermined amount.

12. In apparatus for processing artificial textile yarns, a yarn processing unit as claimed in claim 11 wherein said take-up roller is positively driven at substantially the same peripheral speed as said processing roller, and wherein said idler roller is replaced with a plurality of small diameter idler rollers having substantially parallel axes positioned at a slight angle to said processing roller and adapted to operate in a liquid medium, and around which the yarn in process is passed to effect a flexing of said yarn.

13. In apparatus as claimed in claim 11, friction feed and take-up rollers having rubber surfaces.

14. Apparatus as claimed in claim 11 wherein said yarn processing roller adapted to carry the yarn in a liquid has a surface comprising a phenol-aldehyde resin.

15. Apparatus as claimed in claim 11, including an idler pulley over which the yarn passes from the supply bobbin to the yarn processing roller, said pulley being positioned at a distance from said supply bobbin at least about three times the wrapped length of said supply bobbin to reduce the angularity of the yarn as it is unwound from the ends of said supply bobbin.

16. Apparatus as claimed in claim 11, including a traverse mechanism, and an idler pulley over which the yarn passes from the yarn processing roller to the take-up bobbin, said pulley being mounted upon said traverse mechanism at a distance from said yarn processing roller at least about three times the wrapped length of said take-up bobbin to reduce the angularity of the yarn as it is unwound from the ends of said supply bobbin.

17. In a yarn processing apparatus as claimed in claim 11, means for setting or stabilizing the yarn, which comprises a spray or jet of heated liquid directed against the yarn as it passes onto the bobbin.

18. In a yarn processing apparatus as claimed in claim 11, means for setting or stabilizing the yarn, which comprises a heated liquid bath positioned so as to maintain a film of the heated liquid on the take-up roller frictionally engaging the take-up bobbin, thereby carrying heated liquid in contact with the yarn being wound.

LEE C. HOSFIELD.
